APPARATUS FOR TURNING WOOD HEELS

Justin P. Quirk and Ludwig G. P. Hafner, St. Louis, Mo., assignors to United Wood Heel Company, St. Louis, Mo., a corporation of Delaware

Application December 29, 1947, Serial No. 794,218

8 Claims. (Cl. 12—42)

1

This invention relates to apparatus for turning shoe heels.

An object of the invention is to provide apparatus capable of turning a heel blank automatically to shape the heel and, then after the heel is shaped, to perform a subsequent operation, such as grading, upon the heel.

Other objects and advantages will be apparent from the following description of the invention taken in connection with the accompanying drawings.

Fig. 1 is an elevational view of an embodiment of my invention;

Fig. 2 is a horizontal sectional view on line 2—2, Fig. 1;

Fig. 3 is a plan view, diagrammatic in character;

Fig. 4 is a diagrammatic view showing a cutter, heel blank support and some mechanism in elevation, to illustrate the method herein described;

Fig. 5 is a view similar to Fig. 4 taken at a point 90° removed from Fig. 1; and

Fig. 6 is a view similar to Fig. 4, showing the relationship of the elements of a different phase in the operation.

A condensed description of some of the salient points and important characteristics of the apparatus at once will assist in understanding the later detailed description.

The specific embodiment of the invention illustrated in the drawings includes a wood heel turning machine arranged and adapted to turn a heel blank B while in engagement with a high speed rotating cutter 11. A seat 12 for the blank B is mounted on the upper end of a shaft 13, the shaft being driven through a transmission system by a motor 14. A clamp 15 is arranged and adapted to engage the top of the blank B coaxial with the seat 12 to hold the blank on the seat while it is being turned and shaped by the cutter 11.

A second tool comprising a grading saw 16 is carried by a pivotal support 17 to move into operative position to grade the blank after it has been turned and shaped by the cutter 11. A spring pressed dog 18 is also carried by the support 17 and is positioned and arranged to engage a tooled surface of the heel blank and thereby hold the blank on its seat 12.

A cam 19 secured to and rotating with the shaft 13 is constructed and arranged to release the clamp 15 at a predetermined time immediately after the heel has been shaped by the cutter 11. A second cam 20, driven also by the motor 14 and therefore in timed relationship to the cam 19, has

2

a follower and connected mechanism to move the support 17, and with it the saw 16 and dog 18 to operative positions.

It may be understood, therefore, that after the blank B has been turned and shaped by the cutter 11, the clamp 15 is automatically released, and the tool support 17 is swung to bring the dog 18 into holding position against a tooled surface of the blank and to bring the support 17 into position for grading the blank.

The mechanism for turning the blank is illustrated substantially in our copending application, Serial No. 728,430, filed February 14, 1947, (Figs. 25, 26, 27, and 28) and application, Serial No. 789-154, filed December 3, 1947. The method of turning the heel described and claimed in our copending application, Serial No. 779,400 filed October 11, 1947, is intended to be followed in operating the machine.

20 The turning machine has a base 21 mounting two vertical gibs 22 in which a frame 23 slides. This frame supports a cradle 24 which is mounted by a horizontal pivot 25 on the upper end of the frame 23.

25 The shaft 13 is journaled in the cradle 24 and carries at its upper end the seat 12 for the blank B. The shaft 13 is secured to a wheel 26, driven by a worm 27 on a shaft 28.

30 The clamp 15 is arranged and adapted to engage the top of the blank B coaxial with the seat 12 and the shaft 13. It includes a shaft or rod 29 mounted in a slide or bore on the cradle 24, with an overhanging arm 30 at its top and a cam engaging arm 31 at its bottom. The clamp also 35 includes heel engaging dog 32 pivotally suspended from the arm 30. The lower arm 31 follows a circular cam supported on and turning with the shaft 13. The clamp is urged to open position by a coil spring 34 about the rod 29 and is moved to closed or clamping position by the cam 19.

40 A cam shaft 35 is supported on and journaled in the frame 23. This shaft is driven through a wheel 36 on the shaft and a worm 37 on a shaft 38, which is connected coaxially with the shaft of the motor 14.

45 The shaft 13, on which the blank B is mounted, and the cam shaft 35 are rotated in synchronism by the motor 14 through a transmission presently described. A stub shaft 40, journaled in and supported by the cradle 24 is connected by miter gears 41 to the shaft 28 (which drives the shaft 13). Similarly, a stub shaft 42 is connected by miter gears 43 to the shaft 38 (which drives the cam shaft 35, and is driven by the motor 14).

The stub shafts 40 and 42 are connected by a universal joint 44 and a slip joint 45.

The cam shaft 35 carries the cam 20, for shifting the second tool, as described briefly above, and also a cradle-rocking cam 46, and cutter shifting cam 47. The cradle-rocking cam 46 has contact with a follower 48 in the form of an arm rigid with and depending from the cradle 24. A follower and mechanism, not shown, but illustrated and described in detail in our copending application, Serial No. 728,430, is constructed and arranged to shift the cutter 11 toward and away from the blank B.

A lift cam 49, annular in form, is mounted on a base of the vertical gibs 22 and surrounds the cam shaft 35. This shaft has rigidly secured to it and arranged to rotate therewith a normally extending roller shaft 50, upon which is mounted a lift cam roller 51 in contact with the lift cam 49. Thus, as the cam shaft 35 rotates, the shaft 35, and with it the frame 23, will be lifted or lowered corresponding to the contour of the lift cam 49.

It may now be understood that as the cam shaft 35 is rotated, the necessary heel shaping movements are imparted to the blank B and the cutter 11, while the blank B is mounted on and turned by the shaft 13, the shafts 13 and 35 being rotated in synchronism by a single source of power, the motor 14. These heel shaping movements include: (a) relative shifting between the blank and the cutter, accomplished by and depending upon the contour of the cam 47; (b) change in inclination of the blank relative to the cutter, accomplished by rocking the cradle 24 through action of the cam 46; and (c) changing the vertical position of the blank relative to the cutter, accomplished by lifting the frame 23 through the action of the cam 49.

The lower cam 20, secured to the cam shaft 35 is arranged and adapted to move the support 17 for the second tool, or grading saw 16, into operative position after the heel blank B has been shaped by the cutter 11. The details of construction of this second tool, its support and associated mechanism will now be described.

The support 17 rests on a hollow pedestal 60, through which extends a shaft 61, rigidly connected to the support 17 at its upper end and having a gear 62 at its lower extremity by which it is moved or controlled by the cam 20. The gear 62 is engaged by a rack 63 slidably supported in a fixture 64 on the lower side of the base 21. The rack 63 carries at one end a cam roller 65 in contact with the cam 20. The shaft 61 is biased with relation to the fixed pedestal 60, through which it extends, by a spring 66, to an operative position.

It may now be understood that the cam 20 is so shaped as to present a low surface to the roller 65 after the blank B has been shaped by the cutter 11, thus permitting the spring 66 to bias the shaft 61 so as to rotate the support 17 toward a position (as shown in full lines, Fig. 3) in which the saw 16 is in engagement with the blank B. After the functions of the saw have been completed, while the mechanism including the cam shaft 35 continues to rotate, the cam 20 moves the rack 63 to rotate the shaft 61 and tool support 17 to inoperative positions (as shown in dotted lines, Fig. 3).

The frame of the support 17 journals a jack screw 67 operable by a hand wheel 68. A fol-

lower 69 is threaded on the screw 67 and is rigid with a block 70. A bracket 71 is secured to the block 70 by a pivot pin 72, so that the inclination of the bracket and its supported devices may be adjusted. The bracket 71 carries a motor 72a, while a second bracket 73, rigid with the frame of the motor 72a, supports a spindle 74 for the saw 16, the spindle being driven through a belt by the motor 72a. The bracket 73 carries an arm 75 to support the spring pressed dog 18.

The dog 18 is a roller mounted on the end of a tubular member 76, which telescopes a rod 77, pinned rigidly to the supporting arm 75. A spiral spring 78 in the tubular member 76 is arranged and adapted to urge that member to an extended position.

In the preceding description, the method of operation has been mentioned. It is appropriate, nevertheless, to give a connected description of the operation. It may be understood at the outset that the device may be and preferably is operated to practice the method described and claimed in our copending application, Serial No. 779,400. That is to say, the blank B is turned continuously in one direction for the major portion of one revolution against the cutter 11, while heel shaping movements are imparted to the blank, to completely shape the heel.

Assuming the device is in starting or loading position, the motor 14 will be stopped, or it may be disconnected by a clutch. The cam 19 will be in position to release the clamp 15, through the action of its spring 34 so that the engaging dog 32 will be in elevated position, to permit the blank to be placed upon the seat 12. The operation of the machine may then be started and the shafts 13 and 35 will begin turning.

The cam 19 is so shaped as to cause the dog 32 to descend immediately upon the blank to clamp it in position. The cam 47, by mechanism not shown, will move the cutter toward and into cutting engagement with the blank, and also shift the cutter during cutting engagement to give shape to the blank. The cam 46 will cause the cradle 24 to rock, and the cam 49 will cause vertical adjustment of the frame 23. Thus, the necessary heel shaping movements will be imparted to the blank while it is in engagement with the cutter 11.

The turning of the heel will be completed in less than one revolution, or approximately 270°. During the remaining portion of the revolution, the second tool is made to complete its functions.

The cam 20 is shaped to permit the spring 66 to swing the support 17 and the saw 16, as well as the engaging dog 18 into operative position, as soon as the heel has been turned. The cam 19 is shaped to release the clamp 15 at substantially the same time, or as soon as the dog 18 has moved into firm engagement with the blank B. The dog or roller 18 remains in firm contact with a tooled surface on the blank B while the saw 16 is grading the blank. Because the blank is held by this means, the clamp 15 may be released to permit the operation of the saw. This is important since it would be impractical to grade the heel while held by the clamp.

The operation of the saw will have been completed by the time the blank B has been turned one complete revolution, or to the starting position. The machine can then be stopped manually by stopping the motor, or automatic means, either a switch or clutch may be provided to stop

it, or to interrupt movement for a predetermined period.

The second or auxiliary tool has been illustrated as a grading saw, but the invention may be applied with appropriate modifications to other tools such as a paneling tool. The invention has been shown as embodied in a machine adapted for turning a blank against a high speed cutter. It may be understood, nevertheless, that the primary turning may be in connection with another tool such as a sander, as shown and described in our copending application, Serial No. 789,454.

The machine described above may preferably be operated to practice a novel method of turning wood heels, as geographically shown in Figs. 4, 5 and 6, and described below.

The blank B is turned about a single or constant axis, this axis coinciding with the axis of the completed heel and perpendicular to the tread thereof. The relative position of the blank, while being turned on this axis is shifted, both to bring the blank into and out of engagement with the cutter, but also to give the blank shaping movements. Also, while the blank is in engagement with the cutter, other heel shaping movements are imparted to the blank without shifting the axis of the blank about which it is rotated. It is moved up and down approximately along its axis, and it is tilted, or its axis is tilted.

This method results in many advantages. By using this method it is much easier to arrange guides or cams for effecting the necessary heel shaping movements, than where, as in previous practice, the axis of turning shifted considerably within the blank during the turning operation. Furthermore, it is much easier to tool for subsequent operations on the heel.

It will be obvious that, while the apparatus particularly described herein, may be arranged to turn the blank according to this method, this is preferable only and not necessary. It will also be obvious that machines or tools of widely different characteristics from the herein described apparatus may be employed for practicing the method.

Some further discussion of the method may be helpful in understanding it and practicing it. In a particular heel to be produced the "wedge" of the heel is known, that is, the inclination of the heel seat relative to the tread. The angle of that wedge is then used as the angle of the seat 12, or rather the angle at which the seat 12 meets a plane or line radial or perpendicular to the axis A of the heel and a shaft 13 by which the heel blank B is turned. It will be noted that the saw 16, as it grades the blank and thereby forms the tread of the heel, cuts perpendicular to the axis A.

In the apparatus shown, the relative movements between the blank and cutter is accomplished by shifting the cutter, although this may be accomplished obviously by shifting the blank. Different apparatus for doing this both ways is disclosed in our copending application, Serial No. 728,430.

The blank is moved up and down, by the apparatus herein disclosed, by shifting the frame 23 which carries the blank B. This is approximately along the axis of the blank, but not exactly so, because the cradle 24, which carries the turning shaft 13 may be and is rocked on the frame to produce another heel shaping movement.

Various changes may be made in details of con-

struction and operation, within the scope of the appended claims, without departing from the invention. Additions and improvements may be made while retaining the invention and its benefits, and parts of the invention may be used without the whole.

We claim:

1. In a wood heel turning machine, having a tool for shaping a heel while its blank is rotated, a jack for holding the heel blank, and means for rotating the jack, the combination comprising a cam driven by said means, a second tool for operating on said blank, and mechanism under the control of said cam for moving the second tool into engagement with the blank.
2. In a wood heel turning machine, having a tool for shaping a heel while its blank is rotated, a jack for holding the heel blank including a seat upon which the blank is mounted and a releasable clamp for holding the blank on the seat, and driving means for rotating the seat and thereby the blank, the combination comprising a second tool for operating on said blank, a cam driven by said means, mechanism under the control of said cam for moving the second tool into engagement with the blank, a second cam driven by said means, and mechanism under the control of said second cam for releasing said clamp.
3. In a wood heel turning machine, having a tool for shaping a heel while its blank is rotated, a jack for holding the heel blank including a seat upon which the blank is mounted and a releasable clamp for holding the blank on the seat, and driving means for rotating the seat and thereby the blank, the combination comprising a spring pressed dog arranged and adapted to engage a tooled surface of the heel blank and hold the blank on the seat, a plurality of cams driven by said driving means and thereby in fixed relationship with said driving means and one with the other, mechanism under the control of one of said cams for releasing said clamp, and mechanism under the control of another of said cams for moving said dog into position to engage the heel blank and thereby hold it on its seat when the said clamp is released as aforesaid.
4. In a wood heel turning machine, having a tool for shaping a heel while its blank is rotated, a jack for holding the heel blank including a seat upon which the blank is mounted and a releasable clamp for holding the blank on the seat, and driving means for rotating the seat and thereby the blank, the combination comprising a second tool for operating on said blank, a spring pressed dog arranged and adapted to engage a tooled surface of the heel blank and hold the blank on the seat, a plurality of cams driven by said driving means and thereby in fixed relationship with said driving means and one with the other, mechanism under the control of one of said cams for releasing said clamp, and mechanism under the control of another of said cams for moving the second tool and the dog into operative position relative to the blank; whereby after the blank is turned and shaped by the first tool, the jack clamp is released, the dog is brought into holding position against a tooled surface of the blank, and the second tool is brought into position for operation on the blank.
5. In a wood heel turning machine, having a tool for shaping a heel while its blank is rotated, a seat upon which the blank is mounted, and driving means for rotating the seat and thereby the blank, the combination comprising a clamp arranged and adapted to engage the top of the

blank coaxial with seat and thereby hold the blank on the seat while the blank is being turned and shaped by said tool, a second tool for operating on said blank, a pivoted support for said second tool, a spring pressed dog fixed to said support and arranged and adapted to engage a tooled surface of the heel blank and hold the blank on the seat, a plurality of cams driven by said driving means and thereby in fixed relationship with said driving means and one with the other, mechanism under the control of one of said cams for releasing said clamp, and mechanism under the control of another of said cams for rotating said tool support; whereby after the blank is turned and shaped by the first tool, the clamp is released, and the tool support is swung to bring the dog into holding position against a tooled surface of the blank and to bring the second tool into position for operation on the shaped blank.

6. In a wood heel turning machine, having a tool for shaping a heel while its blank is rotated, a jack for holding the heel blank, and means for rotating the jack, the combination comprising a second tool for operating on said blank, a pivoted support for said second tool, a cam driven by said driving means, and mechanism under the control of said cam for rotating said tool support; the tool support being constructed and arranged to swing said second tool into and out of engagement with the heel blank, whereby after the blank is turned and shaped by the first tool, the tool support is swung to bring the second tool into engagement with the blank for a subsequent operation by said second tool.

7. In a wood heel turning machine, having a high speed cutter for shaping a heel while its blank is rotated, a seat upon which the blank is mounted, and driving means for rotating the seat and thereby the blank, the combination comprising a clamp arranged and adapted to engage the top of the blank coaxial with the seat and thereby hold the blank on the seat while the blank is being turned and shaped by said cutter, a grading saw, a movable support for said saw arranged and adapted to move the saw into proper posi-

tion to grade the blank on said seat, a spring pressed dog arranged and adapted to engage a tooled surface of the heel blank and hold the blank on the seat, and mechanism under the control of said driving means constructed and adapted to release said clamp, after the blank has been turned and shaped by said cutter, and mechanism under the control of said driving means to move the support to bring the saw into cutting position for grading the shaped blank, and to move the dog into holding position against the tooled surface of the blank to hold the shaped blank in position on the seat while it is being graded as aforesaid.

15 8. In a wood heel turning machine, having a tool for shaping a heel while its blank is rotated, a jack for holding the heel blank, and means for rotating the jack, the combination comprising cams associated with the rotating means for giving relative shaping movements between the jack and tool, a second tool for operating on said blank, another cam driven by said rotating means, and mechanism under the control of said last mentioned cam for moving the second tool into engagement with the shaped blank; the cam being constructed and arranged to cause the shaping of the heel by the first tool from breast edge to breast edge, during a portion of a revolution of the blank, and then to bring the second tool into engagement with the shaped blank for its operation during the remaining part of said revolution.
